(57) **CLAIM**

The ornamental design for an eyeglass accessory, as shown and described.

DESCRIPTION

FIG. 1 is a front perspective view of an eyeglass accessory of the present invention;

FIG. 2 is a front elevational view thereof;

FIG. 3 is a right side elevational view thereof, the left side elevational view being a mirror image thereof;

FIG. 4 is a top plan view thereof;

FIG. 5 is a rear elevational view thereof; and,

FIG. 6 is a front perspective view of a portion of the accessory of FIG. 1 showing an eyeglass and leash in phantom lining, an eyeglass and leash being one non-limiting environment in which the new design can be used.

The broken line portions of the drawings are for illustrative purposes only and form no part of the claimed design.
